US00D998401S

(12) **United States Design Patent** (10) **Patent No.:** **US D998,401 S**
(45) **Date of Patent:** **** Sep. 12, 2023**

(54) **DISPENSING DEVICE**

- (71) Applicant: **Hydration Labs, Inc.**, Charlestown, MA (US)
- (72) Inventors: **Eliza Becton**, Charlestown, MA (US); **Tom Chavara**, Charlestown, MA (US)
- (73) Assignee: **Hydration Labs, Inc.**, Charlestown, MA (US)
- (**) Term: **15 Years**
- (21) Appl. No.: **29/748,625**

(22) Filed: **Aug. 31, 2020**

(51) **LOC (14) Cl.** **07-01**
(52) **U.S. Cl.**
USPC **D7/306; D7/311**

(57) **CLAIM**

The ornamental design for a dispensing device, as shown and described.

DESCRIPTION

FIG. 1 is a top perspective view of a first embodiment of our new design for a dispensing device;

FIG. 2 is a bottom perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof;

FIG. 8 is a bottom plan view thereof;

FIG. 9 is a top perspective view of a second embodiment of our new design for a dispensing device;

FIG. 10 is a bottom perspective view thereof;

FIG. 11 is a front elevation view thereof;

FIG. 12 is a rear elevation view thereof;

FIG. 13 is a left-side elevation view thereof;

FIG. 14 is a right-side elevation view thereof;

FIG. 15 is a top plan view thereof; and,

FIG. 16 is a bottom plan view thereof.

The broken lines shown in the drawings illustrate portions of the dispensing device that form no part of the claimed design.
